UNITED STATES PATENT OFFICE.

ARMAIS ARUTUNOFF, OF THREE RIVERS, MICHIGAN.

ELECTRICALLY-DRIVEN PUMP.

Application filed February 28, 1925. Serial No. 12,274.

This invention relates to improvements in electrically driven pumps. It relates particularly to the protective means for the electric motor of such a pump when the 5 pump and motor are submerged under water, oil or dangerous fluids.

The objects of the invention are to provide protective means for the electric motor of such a pump.

10 The objects in detail are:

First, to provide an improved stuffing box with lubricating device and protecting means.

Second, to provide in such connection a 15 pumping device for exerting back pressure for the protection of the motor, associated with valve means.

Third, to provide improved means of collecting any leakage water and returning it 20 automatically to the supply to protect said motor.

Further objects relating to details and economies of construction and operation will appear from the detailed description to 25 follow.

I accomplish the objects of my invention by the devices and means described in the following specification. The invention is clearly defined and pointed out in the claims.

30 A structure showing a preferred embodiment of my invention is illustrated in the accompanying drawing, forming a part of this application, in which:

Fig. I is a detail vertical longitudinal 35 sectional view of the upper part of the structure, divided and separated from the auxiliary protecting chamber means at the base.

Fig. II is a similar detail of the auxiliary 40 protecting chamber means showing and repeating the part of the drawing of Fig. I which shows the connection to the bottom of the motor casing, the views being vertical sectional views with parts shown in full 45 lines where desirable to make the same clear.

Similar numerals of reference refer to 50 similar parts in the views and the parts will be identified by their numbers.

The pump shown is of the vertical type.

1 is the electric motor casing; 2 is the field 50 magnet; 3 is the armature; 4 is the motor shaft; 5 and 6 are the bearings for the motor shaft; and 7 is the oil circulating means for the lubrication of the motor, all of standard construction, to which details this invention 55 does not pertain.

8 is the stuffing box for the motor shaft; 9 is the drive shaft for the pump; 10 is the coupling for the motor shaft to the pump shaft; 11 is the pump impeller; 12 is the 60 pump casing; and 13 is the delivery pipe from the pump. The pump and other parts are of the usual construction for this class of work.

14 is the coupling chamber having a central conical upwardly-inwardly-projecting sleeve portion 15 from the bottom, the stuffing box 8 being at the upper end of said sleeve. A reservoir is thus formed around the sleeve within the coupling chamber 14. 70 16 is the insulated auxiliary chamber secured to the bottom of the motor casing by suitable screw-thread 161, or otherwise.

17 is the auxiliary pump casing on top of the coupling chamber 14 containing the protecting pump impeller 18 which is secured to the pump shaft 9. This impeller 18 surrounds an upwardly-projecting sleeve 181 on the upper end or head of the coupling casing. The centrifugal impeller, or other 80 pump arrangement, creates a back pressure at this point to protect the coupling chamber when the pump is in operation.

19 is the main stuffing box shell which is preferably a central axial continuation of 85 the auxiliary pump casing 17. The gasket is divided into parts 191 and 192, which are separated by suitable washers and are retained in place by the gland 193 within the auxiliary pump chamber 17. The upper 90 end of the stuffing box shell 19 serves as the coupling to the main pump casing 12. A valve shoulder or collar 20 is on the pump shaft and drops down against a valve seat 201 formed in the casing underneath, and 95 thus forms a valved closure to protect the motor casing, making a very effective closure and protection at that point when the

pump is at rest. This valve may be located at any place on either the pump or motor shaft to protect the motor.

When the motor is started this valve collar 5 is automatically raised from its seat, either by the action of the electric motor or by the action of the pump impeller or otherwise, so that it revolves when the pump is in action entirely out of contact with its seat, to avoid 10 undue friction and wear.

I secure this result in various ways. In the electric motor it will be noted that the armature is down a little in the field and when the motor is started these parts have 15 an effect to lift up and separate or tend to separate the valve collar from its seat. The impeller 11 is preferably designed to have a similar effect to raise the pump shaft and lift the valve off its seat. Of course, a 20 centrifugal governor could be provided to do the same work mechanically. This is not shown, as such action in that behalf would be readily understood by any skilled mechanician.

25 Grease is supplied under pressure to the central space between the divided gasket parts 191, 192. This presses the packings outwardly and preserves a very tight joint when the grease is thus supplied under pressure, completely sealing the same. Grease is supplied through the pipe 21 delivering from the cylindrical grease chamber 211 containing the grease 212 which is forced out by the piston 213. The piston is forced yielding- 30 down by the coil spring 214. The pressure of the surrounding fluid has the same tendency.

The grease supply is controlled automatically by suitable automatic valve mechanism 40 30. This comprises a cylinder 301 containing piston 302 having a piston rod valve stem 303 terminating in a valve 304, to cut off the supply 21. The piston 302 is held normally in elevated position, thus holding 45 the valve 304 open by coil spring 305 beneath the under side of the piston and within the cylinder head. The opposite end of the cylinder 301 is connected by tube or passage 306 to the pressure side of the pump, 50 preferably to the chamber 12 as shown. It will be clear that when the pump is at rest no pressure is exerted on the piston and the spring lifts the same, opens the valve and permits the grease to be delivered under 55 pressure between the parts of the gasket packing. This forces them tightly in position and fills the space under a higher degree of pressure than the surrounding medium, making an effective sealing and closure at 60 that point.

When the pump impeller 11 starts and creates pressure, that pressure is delivered to the cylinder 301 and forces the piston down and cuts off the supply of grease. This is

desirable because if the grease is delivered 65 constantly under pressure it is greatly wasted by being forced past the pump shaft. It is only necessary or desirable to have the grease present under pressure when the pump is at rest to afford a seal at that point. 70

Under ordinary circumstances the protection thus provided is sufficient to protect the motor. However, if the pump is to stand for a long time accidents may happen to this equipment. Further than that, the pipe 75 supplying grease under pressure may become clogged from a piece of waste or other obstruction, or it may otherwise fail of operation, in which event I have provided additional and other,—what may be styled emergency,—protection.

Within the coupling chamber, as I have indicated, there is provided a reservoir which is so located as to collect any leakage 85 of water or other fluid that is being pumped which may leak within the same.

Leading down from this chamber 14 is a pipe 141 or other connection delivering into an auxiliary reserve chamber 31 above the auxiliary insulated discharge chamber 16, 90 being a section or division of the casing forming that chamber. This is provided with a bottom 162 through which is disposed a trap 163 provided with a check valve 164 (see Fig. II), so that fluid of leakage 95 may be discharged from the coupling chamber down into this auxiliary chamber and flow out down into the discharge chamber 16 past the check valve 164 which opens in that direction. In the bottom of chamber 16 is a 100 valved outlet 165, closed by the spring valve 166, so that the contents may be forced out.

Within the chamber is a float 167 connected to control the switch 168 which controls the circuit that supplies current 105 through the conductor 169 to a heating element 32.

It will thus be seen that when water or fluid accumulates in the coupling chamber, it drops down through the pipe or connection 110 141 into the auxiliary chamber 31, whence it delivers downwardly through the valved trap 163 into the insulated discharge chamber 16. When the float is raised sufficiently 115 to close the switch, the heating element 32 immediately heats the water. It is of sufficient capacity to raise the same to the boiling point and develop steam and pressure within this insulated discharge chamber. As soon as sufficient pressure is developed, the 120 spring-controlled valve 166 at the bottom is forced open and the water is discharged. This permits the float 167 to drop, opens the switch, and cuts off the current, the pressure 125 soon drops because of the discharge of the contents, the check valve 164 can again open, and any further accumulation can enter as before and be discharged in the same way.

This affords an additional protection for the electric motor driving the pump.

While I have shown the chamber and the heat elements in a casing beneath the motor casing, it is clear that these parts may be otherwise supplied or otherwise supported. The form and arrangement is of no consequence, so far as action is concerned. The particular form is very convenient and effective in its relation to the other parts. The heating element can be operated from an independent circuit, although I prefer to operate it from the circuit for the motor controlled by the main switch 33, interposing suitable resistances 34 and providing additional conductor 35, in a well-known manner as seen from the illustration.

While I have shown a means for raising the temperature of the water or other fluid to the boiling point, to develop pressure to discharge the same, and a float control for the circuit, modifications of the structure will be apparent to those skilled in the art, and I desire to claim the invention broadly as well as specifically, as shown in the appended claims.

Having thus described my invention, what I claim as new and desire to secure by Letters Patent is:

- 30 1. In an electric pump, the combination of a pump, a shell axially connected thereto forming a casing for an electric motor, separated into a coupling chamber between the pump and the motor, and provided with an insulated discharge chamber for leakage below, a stuffing box within the coupling chamber, an electric motor within the motor chamber, the armature of which is below the field level when at rest so that it will be somewhat elevated when the motor starts, an auxiliary chamber with a stuffing box shell at its upper end axially disposed between the coupling chamber and the pump, an upwardly-projecting sleeve in the auxiliary pump chamber and a pump impeller secured to the shaft at that point to create back pressure and prevent the flow of liquid toward the motor, divided gasket packings within the said stuffing box shell, a reservoir for grease with pressure piston therein and connection therefrom to the central space between said gasket packing parts to insure pressure in excess of the surrounding medium, an automatic cut-off for the grease supply comprising a cylinder with a piston and rod terminating in a suitable cut-off valve, a spring for holding the same normally open, and a connecting passage from the pressure side of the main pump to deliver pressure to the cylinder to actuate the piston to shut off the grease when the pump starts, a valve collar on the pump shaft, a valve seat therefor against which the valve closes when the pump is at rest and which opens when the pump starts, and a source of electric supply for said electric means, coating substantially as described. 100
- 40 2. In an electric pump structure, the combination of a pump, a shell axially connected thereto forming a casing for an electric motor, separated into a coupling chamber between the pump and the motor, a stuffing box within the coupling chamber, an electric motor within the motor chamber, the armature of which is below the field level when at rest so that it will be somewhat elevated when the motor starts, an auxiliary chamber with a stuffing box shell at its upper end axially disposed between the coupling chamber and the pump, an upwardly-projecting sleeve in the auxiliary pump chamber and a pump impeller secured to the shaft at that point to create back pressure and prevent the flow of liquid toward the motor, divided gasket packings within the said stuffing box shell, a reservoir for grease with pressure piston therein and connection therefrom to the central space between said gasket packing parts to insure pressure in excess of the surrounding medium, an automatic cut-off for the grease supply comprising a cylinder with a piston and rod terminating in a suitable cut-off valve, a spring for holding the same normally open, and a connecting passage from the pressure side of the main pump to deliver pressure to the cylinder to actuate the piston to shut off the grease when the pump starts, a valve collar on the pump shaft, a valve seat therefor against which the valve closes when the pump is at rest and which opens when the pump starts, and a source of electric supply for said electric means, coating substantially as described. 110
- 45 3. In an electric pump structure, the combination of a pump, a shell axially connected thereto forming a casing for an electric motor, separated into a coupling chamber between the pump and the motor, and provided with an insulated discharge chamber for leakage below, a stuffing box within the coupling chamber, an electric motor within the motor chamber, an auxiliary chamber with a stuffing box shell at its upper end axially disposed between the coupling chamber and the pump, an upwardly-projecting sleeve in the auxiliary pump chamber and a pump impeller secured to the shaft at that point to create back pressure and prevent 120
- 50 4. In an electric pump structure, the combination of a pump, a shell axially connected thereto forming a casing for an electric motor, separated into a coupling chamber between the pump and the motor, and provided with an insulated discharge chamber for leakage below, a stuffing box within the coupling chamber, an electric motor within the motor chamber, an auxiliary chamber with a stuffing box shell at its upper end axially disposed between the coupling chamber and the pump, an upwardly-projecting sleeve in the auxiliary pump chamber and a pump impeller secured to the shaft at that point to create back pressure and prevent 125
- 55 5. In an electric pump structure, the combination of a pump, a shell axially connected thereto forming a casing for an electric motor, separated into a coupling chamber between the pump and the motor, and provided with an insulated discharge chamber for leakage below, a stuffing box within the coupling chamber, an electric motor within the motor chamber, an auxiliary chamber with a stuffing box shell at its upper end axially disposed between the coupling chamber and the pump, an upwardly-projecting sleeve in the auxiliary pump chamber and a pump impeller secured to the shaft at that point to create back pressure and prevent 130

- the flow of liquid toward the motor, divided gasket packings within the said stuffing box shell, a reservoir for grease with pressure piston therein and connection therefrom to the central space between said gasket packing parts to insure pressure in excess of the surrounding medium, an automatic cut-off for the grease supply comprising a cylinder with a piston and rod terminating in a suitable cut-off valve, a spring for holding the same normally open, and a connecting passage from the pressure side of the main pump to deliver pressure to the cylinder to actuate the piston to shut off the grease when the pump starts, a drain from the bottom of the coupling chamber to an auxiliary storing chamber above the insulated discharge chamber, a check valve between said storage chamber and discharge chamber opening in to the same, an electric heating element disposed within the discharge chamber, a float switch for controlling a circuit delivering current to the said heating element, a discharge passage with a spring-pressed valve in the bottom of the discharge chamber to yield under pressure to discharge the contents thereof, and a source of electric supply for said electric means, coacting substantially as described.
4. In an electric pump structure, the combination of a pump, a shell axially connected thereto forming a casing for an electric motor, separated into a coupling chamber between the pump and the motor, a stuffing box within the coupling chamber, an electric motor within the motor chamber, an auxiliary chamber with a stuffing box shell at its upper end axially disposed between the coupling chamber and the pump, an upwardly-projecting sleeve in the auxiliary pump chamber, and a pump impeller secured to the shaft at that point to create back pressure and prevent the flow of liquid toward the motor, divided gasket packings within the said stuffing box shell, a reservoir for grease with pressure piston therein and connection therefrom to the central space between said gasket packing parts to insure pressure in excess of the surrounding medium, an automatic cut-off for the grease supply comprising a cylinder with a piston and rod terminating in a suitable cut-off valve, a spring for holding the same normally open, and a connecting passage from the pressure side of the main pump to deliver pressure to the cylinder to actuate the piston to shut off the grease when the pump starts, and a source of electric supply for said electric means, coacting substantially as described.
5. In an electric pump structure, the combination of a pump, a shell axially connected thereto forming a casing for an electric motor, separated into a coupling chamber between the pump and the motor, a stuffing
- box within the coupling chamber, an electric motor within the motor chamber, divided gasket packings within the said stuffing box shell, a reservoir for grease with pressure piston therein and connection therefrom to the central space between said gasket packing parts to insure pressure in excess of the surrounding medium, an automatic cut-off for the grease supply comprising a cylinder with a piston and rod terminating in a suitable cut-off valve, a spring for holding the same normally open, and a connecting passage from the pressure side of the main pump to deliver pressure to the cylinder to actuate the piston to shut off the grease when the pump starts, and a source of electric supply for said electric means, coacting substantially as described.
6. In an electric pump structure, the combination of a pump, a shell axially connected thereto forming a casing for an electric motor, separated into a coupling chamber between the pump and the motor, a stuffing box within the coupling chamber, an electric motor within the motor chamber, divided gasket packings within the said stuffing box shell, a reservoir for grease with pressure piston therein and connection therefrom to the central space between said gasket packing parts to insure pressure in excess of the surrounding medium, an automatic cut-off for the grease supply controlled from the action of said pump, and a source of electric supply for said electric means, coacting substantially as described.
7. In an electric pump structure, the combination of a pump, a shell axially connected thereto forming a casing for an electric motor, separated into a coupling chamber between the pump and the motor, a stuffing box within the coupling chamber, an electric motor within the motor chamber, an auxiliary chamber with a stuffing box shell at its upper end axially disposed between the coupling chamber and the pump, a sleeve projecting upwardly into the auxiliary pump chamber, and a pump impeller secured to the shaft at that point to create back pressure and prevent the flow of liquid toward the motor, and a source of electric supply for said electric means, coacting substantially as described.
8. In an electric pump structure, the combination of a pump, a motor for driving the same, a stuffing box comprising a transversely divided gasket packing within the same, a reservoir for grease with spring loaded pressure piston therein, open to the action of the surrounding medium, and with connection to the central space between the divisions of said packing, as specified.
9. In an electric pump structure, the combination of a pump, a motor within a suitable casing, an auxiliary pump chamber with a stuffing box shell at its upper end axially

- disposed between the coupling chamber and the pump, an upwardly-projecting sleeve in the auxiliary pump chamber, and a pump impeller means in the auxiliary chamber to create pressure to prevent the flow of liquid toward the motor.

10. In an electric pump structure, the combination of a pump, a motor within a suitable casing, an auxiliary chamber with a stuffing box shell at its upper end axially disposed between the coupling chamber and the pump, and a pump means in the auxiliary chamber to create pressure to prevent the flow of liquid toward the motor.

15. 11. In an electric pump structure, the combination of a pump, an electric motor suitably encased, a coupling chamber between the two, a drain from the bottom of the coupling chamber, an insulated discharge chamber connected to the drain, an electric heating element disposed within the discharge chamber, and an automatic control switch to control the circuit to supply current to the heating element to discharge the contents of the discharge chamber, as specified.

20. 12. In an electric pump structure, the combination of a pump, an electric motor therefor suitably encased, a coupling chamber between said pump and motor, a stuffing box with divided packing, means for delivering grease to said stuffing box under pressure, automatic control therefor connected to the said pump to shut off the grease when the pump starts, a valve collar on the connecting shaft, a suitable seat therefor to protect the motor, means for raising the said valve when the motor starts, a discharge chamber connected to said coupling chamber to receive leakage therefrom, and automatic means in said discharge chamber for discharging the accumulation therefrom, coacting as specified.

25. 13. In an electric pump structure, the combination of a pump, an electric motor therefor suitably encased, a coupling chamber between said pump and motor, a stuffing box with divided packing, means for delivering grease to said stuffing box under pressure, automatic control therefor to shut off the grease when the pump starts, a valve collar on the connecting shaft, a suitable seat therefor to protect the motor, means for raising the said valve when the motor starts, a discharge chamber connected to the said coupling chamber to receive leakage therefrom, and automatic means in said discharge chamber for discharging the accumulation therefrom, coacting as specified.

30. 14. In an electric pump structure, the combination of a pump, an electric motor therefor suitably encased, a coupling chamber between said pump and motor, a stuffing box with divided packing, means for delivering grease to said stuffing box under pressure, automatic control therefor to shut off the grease when the pump starts, a valve collar on the connecting shaft, a suitable seat therefor to protect the motor, means for raising the said valve when the motor starts, a discharge chamber connected to the said coupling chamber to receive leakage therefrom, and automatic means in said discharge chamber for discharging the accumulation therefrom, coacting as specified.

35. 15. In an electric pump structure, the combination of an encased electric motor, an auxiliary pump structure disposed and arranged to create back pressure to protect said motor while in operation, and a stuffing box with grease seal to protect said motor when at rest.

40. 16. In an electric pump structure, the combination of an encased electric motor, an auxiliary pump structure disposed and arranged to create back pressure to protect said motor while in operation, a stuffing box with grease seal to protect said motor when at rest, and a shouldered valve on the shaft acting as a valve to protect the motor when at rest.

45. 17. In a submersible electric pump structure, the combination of a discharge chamber with electric heating element disposed and arranged to pump out the leakage water to protect the motor of said electric pump.

50. 18. In a submersible electric pump structure, the combination of an auxiliary pump, a stuffing box with grease seal in it, a grease chamber with a pressure means to cause a continuous pressure in excess of the surrounding medium, supplying said stuffing box, and a shoulder on the shaft acting as a valve, said combination disposed and arranged to protect the motor of said electric pump.

55. 19. In a submersible electric pump structure, the combination of an auxiliary pump, a stuffing box with grease seal in it, a grease chamber with a pressure means to cause a continuous pressure in excess of the surrounding medium, supplying said stuffing box, a shoulder on the shaft acting as a valve, a discharge chamber with electric heating element, and an outlet and an inlet valve in said discharge chamber, said combination disposed and arranged to protect the motor of said electric pump.

60. 20. In a submersible electric pump, the combination of a pump, a motor below the pump, a stuffing box with grease seal in it, a grease chamber with a pressure means supplying said stuffing box with grease under a continuous pressure in excess of surrounding medium pressure, an automatic cut-off for the grease supply to shut off the grease when the pump starts, and an auxiliary pump device of the impeller type creating back pressure and preventing the flow of liquid toward the motor, said auxiliary pump protecting the motor while in operation and said grease seal protecting the motor while at rest.

65. 21. In a submersible electric pump, the combination of a pump, a motor below the

pump, a stuffing box with grease seal in it, and prevent the flow of liquid toward the
a grease chamber with a pressure means 10
supplying said stuffing box with grease
under a continuous pressure in excess of
surrounding medium pressure, an automatic
5 cut-off for the grease supply to shut off the
grease when the pump starts, and an auxiliary pump device to create back pressure

motor, said auxiliary pump protecting the
motor while in operation and said grease
seal protecting the motor while at rest.
In witness whereof, I have hereunto set
my hand.

ARMAIS ARUTUNOFF.
